STUART PARMELEE MILLER, OF TENAFLY, NEW JERSEY, ASSIGNOR TO THE BARRETT COMPANY, OF NEW YORK, N. Y., A CORPORATION OF NEW JERSEY

DISTILLATION OF TAR

Application filed March 14, 1927. Serial No. 175,075.

This invention relates to improvements in the distillation of tars, and particularly to the utilization of the heat available in the gases produced in coal-carbonization plants, such as coke ovens, to distill tar and to produce pitches and an increased proportion of oils by such distillation. The invention will be described especially with reference to its application to coke ovens.

In the ordinary operation of by-product coke ovens the gases produced by the coking operation pass from the individual ovens through uptake pipes and goose-necks to a collector main common to the ovens of the battery. The gases, commonly known as "foul" gases, leave the ovens at high temperature, e. g., 600° to 700° C. or higher, and carry a considerable proportion of tars and oils. Ordinarily the gases are cooled as rapidly as possible by the application of sprays of ammonia, or ammonia liquor and tar, in the goose-necks and collector main, the heat in the gases being thereby dissipated and lost. The rapid cooling causes separation of the tar containing the heavier oils in the collector main. Further cooling is effected in the cross-over main which connects the collector main to the condensing system and an additional quantity of tar carrying both heavier and lighter oils is thus separated. The collected tar is commonly shipped from the coke-oven plant to a tar-distillation plant for distillation and separation of the oils and the production of pitches of varying qualities. Handling losses, freight charges and distillation costs, including fuel and capital and maintenance expenses for the special equipment required for distillation, add to the cost of production of the end products of the distillation.

It is an object of the present invention to provide a method and apparatus which permit the distillation of tar at a coke-oven plant, utilization of the heat of the coke-oven gases for that purpose, and particularly the production of pitches having varying characteristics and the enrichment of the gases in oil vapors which may be condensed subsequently for recovery of valuable oil constituents.

According to the present invention the heat of the coke-oven gases is utilized immediately after the gases leave the coke ovens to distill tar by spraying or otherwise bringing the tar into intimate contact with the hot coke-oven gases, for example, in a structure connected directly to the uptake pipe from a coke oven and arranged to utilize directly the heat of the gases issuing therefrom. The gases are at relatively high temperature, e. g., 600° to 700° C., or higher, but the temperature will drop owing to absorption of heat therefrom by the tar which is caused to intimately mingle with them. The tar is thus heated and distilled, the vapors of the volatile oil mingling with the coke-oven gases and passing along with them. The extent of the drop in temperature of the gases depends upon the amount, nature and temperature of the tar sprayed in and the interval of contact of the tar with the gases. The tar is introduced into the gases at a plurality of levels so that the gases are subjected in successive zones of tar sprays. The temperature drop and the amount of distillation in each zone will be regulated by the amount, kind and temperature of the tar introduced as well as by the water content of the tar.

The tar supplied at different levels in the still may be the same tar, or heavy and light tars may be supplied at different levels, or oil derived from the tar can be introduced at the upper levels and heavier tars at the lower. Preferably, the still is arranged so that the tars supplied at the different levels therein and thus subjected to the heating effect of the hot coke-oven gases at the varying temperatures of these gases in the still can be withdrawn at the different levels so that the arrangement permits the production of different grades of pitches or tars in a single operation. Thus, for example, heavy tar or pitch can be supplied at the lower levels and being subjected to the highest available temperature therein can be distilled to produce heavier pitches whereas the lower temperature at the upper levels can be utilized to partially distill tars or to dehydrate the same in preparation for further distillation in the lower levels or in other distillation apparatus.

Ammonia liquor can be added in regulated amounts with the tar in case it is desired to regulate the distillation of the gases and to hold it to a definite limit.

In carrying out the invention the construction of the coke oven and of its by-product recovery system may remain unchanged except in respect to the provision of one or more stills as hereinbefore described. These stills may be connected to the usual uptake pipes of the ovens and to the usual collector main so that the gases and vapors resulting from the distillation will be delivered to the collector main and may be subjected therein to cooling if desired by the use of sprays of ammonia liquor or of tar and ammonia liquor in accordance with the usual practice. The gases and vapors from the collector main may be conducted through the usual cross-over main in which further cooling may be effected and thence delivered to the condensing system in which the vapors are condensed and the resulting oils are separated from the gases. These gases may then be passed through the usual equipment employed in coke-oven condensing systems to recover valuable products leaving the fuel gases for use as such. The tar or tar and oil which may separate in the collector and cross-over mains can be withdrawn and subjected in suitable decanters to separation from the ammonia liquor which may be returned to the collector main for further use as a cooling medium. The separated tar or tar and oil can be returned to the stills for further distillation or subjected to any other suitable treatment.

While all of the ovens of a coke-oven battery may be provided with stills of the character described for the purpose of distilling tar and enriching the gases in volatile constituents of tar, the invention may be applied also by utilizing such stills only in connection with a selected number of ovens. The amount of heat available in the hot coke-oven gases from a battery of coke ovens is many times that required for the distillation of the tar produced by such a battery. Consequently, if all of the ovens are provided with stills it will be necessary to supply tar for distillation from sources other than the battery of coke ovens with which such stills are connected. In a plant where a large number of batteries of coke ovens are operated a single battery can be provided with stills as described, and the tar produced in the entire plant can be distilled therein.

If only a single battery is operated in the plant tar from other plants can be distilled in order to maintain continuous operation in the manner described. Or the tar produced by the battery can be accumulated and distilled at intervals in the manner described.

If tar from other sources than the battery is not available it will be necessary only to provide one or more stills connected to

one or more ovens of the battery, the remaining ovens being connected by means of the ordinary uptake pipes and goose-necks to the common collector main. In this case the battery may be operated in the usual manner, most of the gases being delivered directly to the collector main without utilization of the heat therein and only the gases from the selected ovens will be utilized in the stills for the distillation of tar.

Since the gases which have been utilized for tar distillation are relatively richer in oil vapors than normal coke-oven gases, it may be desirable, particularly where only a few stills are employed in connection with the battery, to provide a separate condensing system for these vapors. Thus, instead of delivering the gases containing the vapors derived from distillation to the ordinary collector main, these gases may be conducted through a separate condensing system including any suitable condensing equipment as, for example, fractional condensers which will permit progressive lowering of the temperature of the gases to predetermined points for the purpose of condensing and separating the oils in fractions having desired characteristics. If more than one still is provided the several stills can be connected to a short collector main and this may be connected in turn to the separate condensing system.

While stills of various forms and construction can be utilized for the purpose of the invention, the preferred arrangement includes a cylindrical structure arranged directly above and connected to the usual uptake pipe which may discharge the gases into the still. A baffle is provided preferably above the end of the uptake pipe to prevent tar from descending into the coke oven. Spray nozzles are arranged at several levels of the still and are connected by suitable pipes to a source or sources of tar or oil under pressure sufficient to cause the tar or oil to be atomized by the spray nozzles. Annular collectors are arranged within the still beneath each of the spray nozzles so as to collect the tar or oil or the pitch formed therefrom after the hot gases have passed therethrough.

The gases entering at the bottom of the still will be forced outwardly by the baffle and will circulate upwardly so that the gases are intimately mingled with the sprays of tar or oil. The gases will be cooled progressively while the tar or oil introduced through each spray nozzle at each successively higher level will be subjected to a lower temperature sufficient, however, to accomplish distillation or partial distillation of the tar or oil in the still.

The extent to which the temperature of the gases will be lowered will depend upon the height of the still, the number of tar sprays, the volume of tar or oil introduced,

the type and temperature of the tar or oil, the amount of water in it, and the velocity of the gases through the still. If the still is sufficiently high the temperature of the gases at the top thereof may be only high enough to dehydrate or dehydrate and distill the lighter oils from the tar. The tar or oil or the pitch formed therefrom is separately collected at each level and can be separately withdrawn through outlet pipes provided for that purpose. In this manner pitches of different consistency and having different qualities can be produced simultaneously in the stills. The pitches produced can be recirculated if desired through the still by introduction thereof at the same or a different level and thus subjected to the desired degree of heat to accomplish the intended purpose.

5 The invention will be further illustrated by the following more detailed description in connection with the accompanying drawings which show apparatus embodying the invention and adapted for the practice of the process, but it is intended and will be understood that the invention is illustrated thereby and is not limited to the details of the apparatus as disclosed.

10 In the accompanying drawings, Fig. 1 is a plan view of a portion of a coke-oven battery embodying the invention;

15 Fig. 2 is an elevation thereof;

20 Fig. 3 is an enlarged detail in section showing the preferred structure of the still; and

25 Fig. 4 is a plan view of a portion of a coke oven illustrating the application of a separate condensing system to the stills.

The invention is of more or less general application to different types and constructions of by-product coke ovens such as Semet-Solvay ovens, Koppers ovens, etc., but will be more particularly described and illustrated in connection with by-product coke ovens of the Semet-Solvay type.

30 Referring to the drawings, 5 indicates the coke oven having a plurality of uptake pipes 6 connected to a collector main 7 from the centre box 8 of which the gases and vapors are delivered through a cross-over main 9 to the condensing system which includes condensers 10. The gases after passage through the condensers 10 may be delivered to an exhauster 11 and thence to the usual equipment provided in coke-oven plants for the recovery of other valuable products from the gases. The goose-necks and collector main may be provided with the usual spray nozzles 12 adapted to be supplied through a pipe 13 with ammonia liquor or ammonia liquor and tar for the purpose of cooling the hot coke-oven gases. The tar which condenses and separates in the collector main can be withdrawn from the centre box through a pipe 14 and delivered to a decanter 15 in which the ammonia liquor is separated from

the tar. The ammonia liquor can be returned then to the spray nozzles for further use as a cooling agent. The tar may be delivered to a collecting tank 16. The tar and ammonia liquor which separate in the cross-over main can be withdrawn and delivered to a decanter 17 in which the ammonia liquor is separated from the tar. The tar can be delivered to a collecting tank 18. The oils separated in the condensers can be withdrawn and delivered to a decanter 19 in which the ammonia liquor is separated and the oils can then be delivered to a collecting tank 20. The structure and the mode of operation thereof as hereinbefore described embody the usual structure and operation of a coke-oven battery with a by-product recovery system.

35 In accordance with the present invention one or more of the ovens of the battery may be provided with stills 21 connected directly to the uptake pipes from selected ovens and to the collector main through suitable goose-necks. The preferred form of still comprises a shell supported in any suitable way above the uptake pipe to which it is connected and having therein a plurality of spray nozzles 22 designed to introduce tar or oil in the form of a spray. The spray nozzles may be connected by pipes 23 to one or both of the tar receptacles, pumps 24 being provided to permit the introduction of the tar under suitable pressure to ensure the proper atomizing of the tar in the still. Annular collectors 25 are disposed beneath each spray nozzle in the still and outlet pipes 26 permit the withdrawal of the collected tar or pitch therefrom. The tar or pitch so withdrawn can be delivered to receptacles therefor and returned if desired to the same or another level of the still to accomplish the further distillation of the tar or pitch. A baffle 27 is disposed preferably above the end of the uptake pipe to prevent tar from falling into the oven and overflow pipes 28 are provided likewise to avoid the possibility that accumulated pitch in the bottom of the still will overflow into the uptake pipe.

40 The still as described is connected through a goose-neck 29 to the collector main near the cross-over main so that the gases carrying vapors produced by the distillation are delivered to the collector main and mingled with the gases from the remaining ovens of the battery. These gases pass then through the cross-over main to the condensing system where the vapors are condensed and separated in the manner hereinbefore described.

45 In the operation of the apparatus the several stills are supplied with tar or oil produced either in the coke-oven battery or in another battery and the tar or oil is subjected to the distilling effect of the high temperature gases from the coke ovens connected to the stills with the result that volatile constit-

uents from the tar or oils are separated and the gases flowing to the collector main are enriched in condensable constituents. The gases thus utilized for distillation are, moreover, more or less freed from tar particles by the scrubbing action of the tar sprays. If the gases from all of the ovens of the battery are thus utilized the resulting gases flowing from the collector main will be enriched very considerably in oil vapors and the yield of oils therefrom will be correspondingly increased. Furthermore, the oils will be cleaner oils than those usually obtained from the condensers of a by-product coke oven.

13 For the reasons hereinbefore noted, it may be desirable in some cases to avoid mingling of these enriched gases with the gases from the remainder of the ovens of the battery, particularly where only a few of the ovens are connected to stills of the character described. In this case it may be desirable to provide, as indicated in Fig. 4, a short collector main 30 to which the several stills are connected so that the enriched gases from these stills are collected separately. A cross-over main 31 may be connected to the short collector main and to a condensing system including, for example, a plurality of fractional condensers 32 designed to effect the progressive cooling of the gases to predetermined temperatures at which the desired oils will condense and separate so that they can be withdrawn as separate products from the system. The gases remaining after condensation can be conveyed through a pipe 33 to the exhauster 11 which maintains the pressure balance of the system.

41 By regulation of the temperature and operation of the stills and the condensers connected thereto different pitches and different types of oils may be obtained.

45 While I have described and illustrated a particular type and construction of a still adapted to accomplish the purposes of the invention, it will be evident that the invention in its broader aspects can be carried out in an apparatus of modified construction in which the hot gases are employed in the manner described for the distillation of tar and 50 the production of pitch and oil vapors therefrom. Various changes can be made, therefore, in the details of operation and arrangement of the apparatus without departing from the invention or sacrificing any of the 55 advantages thereof.

I claim:—

1. The method of distilling tar, which comprises passing hot coke-oven gases through successive sprays of coal tar immediately after the gases leave the ovens, thereby effecting distillation of the tar, the first spray being subjected thereby to the maximum temperature of the gases and each of the succeeding sprays being subjected to gases of progressively decreasing temperatures, and

separately collecting the residue from the distillation of the tar in the successive tar sprays.

2. The method of distilling tar, which comprises passing hot coke-oven gases upwardly 70 through successive sprays of coal tar introduced at different levels immediately after the gases leave the ovens, thereby effecting distillation of the tar, the first spray being subjected thereby to the maximum temperature of the gases and each of the succeeding sprays being subjected to gases of progressively decreasing temperatures, and separately collecting the residue from the distillation of the tar in the successive tar sprays. 80

3. The method of distilling tar, which comprises passing hot coke-oven gases through successive sprays of coal tar introduced at different levels immediately after the gases leave the ovens, thereby effecting distillation 85 of the tar, the tar introduced at the successive levels having different compositions adapted for distillation at the progressively lower temperatures of the gases, and separately collecting the residue from the distillation of the tar at the different levels.

4. The method of operating coke ovens, which comprises forcing the gases from part of the ovens immediately after they leave the ovens, through successive sprays of tar from 95 other ovens arranged at progressively higher levels, drawing off the different pitches at the successive levels, passing the gases and vapors resulting from the distillation to a condensing system separate from that employed for the gases not used for the distillation of tar and recovering condensable products therefrom. 100

In testimony whereof I affix my signature.
STUART PARMELEE MILLER.
